(57) **CLAIM**

The ornamental design for an aircraft tow and steering bar, as shown.

DESCRIPTION

FIG. 1 is a perspective view of the aircraft tow and steering bar showing my new design;
FIG. 2 is a front view thereof;
FIG. 3 is a side view thereof;
FIG. 4 is a top view thereof;
FIG. 5 is a bottom view thereof; and,
FIG. 6 is another perspective view thereof (dashed steering straps are not part of the claimed design).
The breaks in the drawing figures show no specific length.
